UNITED STATES PATENT OFFICE.

GEORGE H. PRENTICE, OF PAINESVILLE, OHIO.

DEVICE FOR PREVENTING THE CREEPING OF RAILS.

No. 828,739.

Specification of Letters Patent.

Patented June 19, 1906.

Application filed March 23, 1906. Serial No. 307,715.

To all whom it may concern:

Be it known that I, GEORGE H. PRENTICE, a citizen of the United States of America, residing at Painesville, in the county of Lake and State of Ohio, have invented certain new and useful Improvements in Devices for Preventing the Creeping of Rails; and I hereby declare the following to be a full, clear, and exact description of the invention, such as will enable others skilled in the art to which it pertains to make and use the same.

This invention relates to improvements in devices for preventing the creeping of rails.

The object of this invention is to provide a meritorious antirail-creeping device which is exceedingly simple and durable in construction and reliable and very effective in its operation, and preferably comprises a metal bar adapted to be secured in position at one side of the rail and projecting forwardly in the direction in which the rail tends to creep and terminating at its forward end in a jaw or rail-clamping portion having a clamping-surface adapted to grip the adjacent longitudinal edge of the base of the rail at one side of the rail, which bar is provided at its forward end with an arm which is arranged at a right angle to the rail and projects from the bar adjacent the said longitudinal edge of the base under and transversely of the rail, and at its free end adjacent the other longitudinal edge of the rail-base is provided with a jaw adapted to clamp or grip the rail-base, so that any tendency of the rail to creep will tend to swing the arm forwardly or actuate the arm into a position diagonally of the rail, and thereby tighten the grip of the jaws or rail-clamping portions.

With this object in view and to the end of realizing other advantages hereinafter appearing this invention consists in certain features of construction and combinations of parts hereinafter described, and pointed out in the claims.

In the accompanying drawings, Figure 1 is a top plan illustrating a rail upon a tie and my improved antirail-creeping device. Fig. 2 is a left-hand end view relative to Fig. 1, in section on line 2 2.

Referring to the drawings, A represents a rail, and a the base of the rail.

B indicates a tie arranged under and transversely of the rail, which tie constitutes a rail-support.

G represents a metal bar which is mounted on the tie at one side of the rail. The bar G

is arranged longitudinally of the rail, and consequently transversely of the tie, and projects a suitable distance beyond the forward side of the tie in the direction in which the rail tends to creep, which direction is indicated by the arrow c, (marked upon the rail in Fig. 1,) and is the direction in which rolling-stock is intended to travel on the rail. The bar G is spiked or otherwise secured to the tie B, as at h. The bar G terminates at its forward end forwardly of the tie in a jaw or rail-clamping portion g, which is provided with a laterally and inwardly facing surface 4, adapted to bear against, and thereby clamp or grip, the base of the rail at the adjacent longitudinal edge of the base. The bar G is provided at its forward end with a laterally-projecting arm 5, which is arranged forwardly of and parallel or approximately parallel with the tie and at a right angle to the rail. The arm 5 extends under and transversely of the rail and preferably consists of a metal piece which is vertically pivoted at one end, as at 6, to the forward end or rail-clamping portion of the bar G. It will be observed that the arm 5 extends from under the jaw g of the bar G at one side of the rail under the rail to the opposite side of the rail and is provided at its free end with a jaw or clamping portion 7, which bears against, clamps, or grips the base of the rail at the longitudinal edge of the rail-base at the last-mentioned side of the rail.

To bring the rail-clamping surface 4 of the jaw g squarely opposite the adjacent longitudinal edge of the base of the rail, the said jaw and the adjacent portion of the arm 5 are somewhat depressed, as shown in Fig. 2, with the said arm arranged below the said jaw, as already hereinbefore indicated.

To accommodate a convenient application of the device to the rail and to cause the jaws or rail-clamping portions to firmly grip the rail when the device is attached to the tie, the clamping-surface 4 of the jaw g has the trend required to cause it to operate as a cam in gripping the rail during the application of the device—that is, the arm 5 is placed in position relative to the rail and tie before the bar G is spiked to the tie, and thereupon the said bar is operated as a lever by swinging it upon the pivot 6 toward the rail, so as to cause the clamping-surface 4 of the jaw g and the clamping portion 7 of the arm 5 to firmly grip the rail, whereupon the bar G is spiked to the tie, as shown. I would also remark

that the bar G is preferably arranged at somewhat of an angle to the rail, as shown in Fig. 1.

What I claim is—

5. 1. The combination, with a rail, and a tie arranged under and transversely of the rail, of a bar arranged upon and transversely of the tie at one side and longitudinally of the rail, which bar is spiked or secured to the tie and has a free end projecting beyond the tie in the direction in which the rail tends to creep and is provided at its said end with a jaw which grips or clamps the adjacent edge of the base of the rail at the aforesaid side of the rail, said end of the bar having a rail-clamping arm arranged under and at a right angle to the rail, which arm terminates at the opposite side of the rail in a jaw for clamping or gripping the longitudinal edge of the base 15 of the rail at the last-mentioned side of the rail so that any tendency of the rail to creep will tend to actuate the arm into a position somewhat diagonally of the rail and thereby tend to tighten the grip of the jaws.
- 15 2. The combination, with a rail, and a tie arranged under and transversely of the rail, of a bar arranged upon the tie at one side of and spiked or secured to the tie, which bar has a free end which projects beyond the tie 20 in the direction in which the rail tends to creep and is provided at its said end with a jaw for clamping or gripping the base of the rail at the aforesaid side of the rail, said end of the bar having a rail-clamping arm arranged under and transversely of the rail, which arm terminates at the opposite side of the rail in a jaw for clamping the rail-base at the last-mentioned side of the rail so that any 25 tendency of the rail to creep will tend to tighten the grip of the jaws.
- 25 3. The combination, with a rail, of a suitably-supported bar arranged at one side of the rail and projecting in the direction in which the rail tends to creep and provided at its forward end with a jaw for clamping or gripping the base of the rail at the aforesaid side of the rail, which bar has a rail-clamping arm which is arranged under and transversely of the rail and terminates at the opposite side of the rail in a jaw for clamping or gripping the rail-base at the last-mentioned side of the rail so that any 30 tendency of the rail to creep will tend to actuate the arm into a position somewhat diagonally of the rail and thereby tend to tighten the grip of the jaws.
- 30 4. The combination, with a rail, and the tie arranged under and transversely of the rail, of a bar secured to the tie and arranged at one side of the rail and having a free end projecting laterally of the tie, with the end of the bar provided with a jaw for clamping or gripping the base of the rail at the aforesaid side of the rail, said end of the bar having a 35 rail-clamping arm which is arranged under and transversely of the rail and terminates at the opposite side of the rail in a jaw for clamping or gripping the rail-base at the last-mentioned side of the rail so that any tendency of the rail to creep will tend to tighten the grip of the jaws.
- 35 5. The combination, with a rail, and a tie arranged under and transversely of the rail, of a bar arranged upon and transversely of the tie at one side and longitudinally of the rail, which bar is spiked or secured to the tie and projects beyond the tie in one direction, with the projecting end of the bar provided with a jaw for clamping or gripping the adjacent edge of the base of the rail at the aforesaid side of the rail, said bar having a rail-clamping arm which is arranged under and transversely of the rail and pivoted vertically to the bar in suitable proximity to the rail-clamping surface of the aforesaid jaw, which arm terminates at the opposite side of the rail in a jaw engaging the longitudinal edge of the base of the rail at the last-mentioned side of the rail so that any tendency of the rail to creep will tend to tighten the grip of the jaws.
- 40 6. The combination, with a rail, of a suitably-supported bar arranged at one side of the rail and projecting in the direction in which the rail tends to creep and provided at its forward end with a jaw for clamping or gripping the adjacent edge of the base of the rail at the aforesaid side of the rail, which bar has a rail-clamping arm which is arranged under and transversely of the rail and pivoted to the bar in suitable proximity to the rail-clamping surface of the aforesaid jaw, which arm terminates at the opposite side of the rail in a jaw for clamping or gripping the longitudinal edge of the base of the rail at the last-mentioned side of the rail.
- 45 7. The combination, with a rail, of a suitably-supported bar arranged at one side of the rail and projecting in the direction in which the rail tends to creep and provided at its forward end with a jaw for clamping or gripping the base of the rail at the aforesaid side of the rail, which bar has a rail-clamping arm which is arranged under and transversely of the rail and pivoted vertically to the bar in suitable proximity to the rail-clamping surface of the aforesaid jaw, which arm terminates at the opposite side of the rail in a jaw for clamping or gripping the rail-base at the last-mentioned side of the rail, and the aforesaid clamping-surface of the first-mentioned jaw being gradually spaced farther from the axis of the arm in the direction of the rear end of the bar.
- 50 8. The combination, with a rail, and a tie arranged under and transversely of the rail, of a bar arranged upon and secured to the tie at one side of the rail and projecting laterally of the tie, with the projecting end of the bar provided with a jaw for clamping or gripping

the base of the rail at the aforesaid side of the rail, which bar has a rail-clamping arm which is arranged under and transversely of the rail and pivoted vertically to the bar in suitable proximity to the rail-clamping surface of the aforesaid jaw, which arm terminates at the opposite side of the rail in a jaw for clamping or gripping the rail-base at the last-mentioned side of the rail, and the first-mentioned jaw and the adjacent portion of the arm being somewhat depressed substantially as and for the purpose set forth.

9. A device instrumental in preventing the creeping of a rail and comprising a bar

provided at one end with a jaw for clamping or gripping the base of the rail at one side of the rail, which bar has an arm vertically pivoted at one end to the bar in suitable proximity to the rail-clamping surface of the aforesaid jaw and provided at its opposite end with a jaw for clamping or gripping the rail at the opposite side of the rail.

In testimony whereof I sign the foregoing specification in the presence of two witnesses.

GEORGE H. PRENTICE.
